UNITED STATES PATENT OFFICE.

HUGO L. HILLER, OF NEW YORK, N. Y.

DESIGN FOR A LACING.

SPECIFICATION forming part of Design No. 33,445, dated October 23, 1900.

Application filed September 29, 1900. Serial No. 31,584. Term of patent 14 years.

To all whom it may concern:

Be it known that I, HUGO L. HILLER, a citizen of the United States, and a resident of the borough of Manhattan, in the city and State of New York, have invented and produced a new and original Design for a Lacing, of which the following is a specification.

The leading feature of my design consists in a lacing provided with a tip having a spiral rib formed thereon, the body of the tip on which the spiral rib is formed presenting a series of threads extending transversely around it in juxtaposition to one another.

In the accompanying drawings, Figure 1 is a view of the lacing, the tip portions being shown in side elevation; and Fig. 2 is a cross-

section through the tip on the line 2 2 of Fig. 1.

The body of the lacing is denoted by A, the body of the tip by B, and the spiral rib by C. 20

What I claim is—

The design for a lacing, substantially as herein shown and described.

In testimony that I claim the foregoing as my invention I have signed my name, in presence of two witnesses, this 21st day of August, 1900. 25

HUGO L. HILLER.

Witnesses:

FREDK. HAYNES,
EDWARD VIESER.
